UNITED STATES PATENT OFFICE

ARTHUR E. SMITH, OF LOS ANGELES, CALIFORNIA

CLOSURE FOR COLLAPSIBLE TUBES

Application filed July 15, 1926. Serial No. 122,565.

This invention relates to closures for collapsible tubes.

The general object of the invention is to provide a valved closure for collapsible tubes wherein means is provided for assuring that the valve will remain closed when pressure is removed from the tube.

Another object of the invention is to provide a collapsible tube closure having an automatic valve with spring means for assuring that the valve will positively close.

Other objects of the invention will be apparent from the following description taken in connection with the accompanying drawings, wherein:

Fig. 1 is a perspective view of a collapsible tube having a closure thereon embodying the features of my invention;

Fig. 2 is a central sectional view through a closure embodying the features of my invention;

Fig. 3 is an end view of the closure;

Fig. 4 is a view similar to Fig. 2 showing the closure perforated and ready for use;

Fig. 5 is a view of the closure showing the operation of extruding the material;

Fig. 6 is a section on line 6—6, Fig. 3;

Fig. 7 is a view similar to Fig. 2 showing a slight modification of my invention;

Fig. 8 is an end view of the closure shown in Fig. 7 with the spring inserted;

Fig. 9 is a section on line 9—9, Fig. 8 with the seal removed and a spring inserted;

Fig. 10 is a view similar to Fig. 8 showing the seal removed;

Fig. 11 is a view similar to Fig. 10 showing the valve in dispensing position;

Fig. 12 is a perspective view of one form of the spring;

Fig. 13 is a detail showing the spring holding members;

Fig. 14 is a perspective view of a collapsible tube having a cap thereon;

Fig. 15 is a central sectional view through the cap shown in Fig. 14;

Fig. 16 is an enlarged plan looking at the end of the closure and showing the manner of puncturing the closure and

Fig. 17 is a sectional view through the closure in position.

Referring to the drawing by reference characters, I have indicated a collapsible tube generally at 10. This tube may contain dentifrice, paste, or other material and the body of the tube is preferably flexible while the end portion 11 is more or less stiff. This end portion 11 is provided with a threaded neck 12 which has a dispensing aperture 14 therein.

The neck 12 is shown as threaded as at 15 although it will be understood that means other than the threads may be used for securing the closure indicated generally at 16 on the neck. This closure 16 as shown in Fig. 2 is preferably made of rubber and comprises a body portion which is provided with a skirt portion 17 and a boss 18. This boss 18 is provided with an indentation or other mark 19 which serves as a cutting line. The boss 18 is normally imperforated and to use the cap the operator will cut the cap along the indentation 19 to provide a slit 20 as shown in Fig. 4.

On opposite sides of the slit I show a wire member 21 which is looped to surround the slit when the latter is cut and which is sufficiently flexible and resilient so that the tendency of this wire member will be to close the slit. The wire member 21 will preferably be inserted in the closure member under tension. To do this, it may be held in a strained position by a narrow stiff member 22 such as shown in Fig. 13 until it is vulcanized in place, after which the member 22 will be removed. The inner portion of the closure member is shown as provided with bosses 23 and 24. These bosses may be of suitable configuration and will be arranged to provide added thickness of rubber which tends to keep the slit 20 closed when pressure is removed from the tube 10. In Fig. 5 the material as shown at 25 is shown as being extruded.

In Fig. 7 I show the closure member 16 as provided with the boss 18 and bosses 23 and 24. The closure in this case is provided with a slit 30 which is molded therein. This pre-formed slit 30 is normally closed by a seal 31 so that in order to use the contents of the tube the operator must first cut off the seal with 10

scissors or other sharp instrument, so that the slit will be exposed.

In connection with this closure having the preformed slit I may use, if desired, a spring member shown in Fig. 12 at 35. This spring closure member is provided with end portions 36 which are adapted to engage the inner wall of the closure adjacent the ends of the slit 31 thus tending to hold the slit elongated and maintaining it with the walls together to retard movement of the material through the slit, and to hold the closure sealed when pressure is removed from the tube 10.

In Figs. 14 to 17 inclusive, I show a slight modification wherein a rubber closure 40 is fitted on a collapsible tube 41. The closure is provided with a dispensing hole 42. This hole 42 is made when the end of the cap is stretched as shown in Fig. 16, by means of a pointed instrument shown at 45. After piercing the implement 45 is removed and when the closure is released the hole 42 at once becomes closed.

When the closure is arranged on the neck 43 of the tube and sufficient pressure is applied the closure will stretch so that the contents of the tube will be dispensed. When pressure is removed the hole 42 automatically closes.

Having thus described my invention, I claim:

1. A closure for a collapsible tube, said closure comprising a flexible member having an end portion thereon, said end portion having a resilient strip therein, said strip extending transverse of said end portion.

2. In combination with a collapsible tube having a flexible body and a relatively-stiff end, a closure secured upon said end, said closure comprising a flexible member having an exposed end portion, said closure having a guide thereon for indicating a cutting line, said closure being imperforate.

3. A closure for a collapsible tube, said closure including a body portion, means to secure said body portion upon a collapsible tube, said closure having a guide thereon to indicate a cutting line and means in the portion of said closure adjacent said guide for rendering said portion less flexible.

4. A closure for a collapsible tube, said closure including a body portion and a portion for engaging a collapsible tube, said body portion having a portion adapted to be cut to form a dispensing slit therein, said closure having bosses thereon to provide portions of added thickness, said bosses being disposed adjacent said portion to increase the tendency of the slit when formed to close.

5. In combination with a collapsible tube having a flexible body and a stiff end, a closure removably secured upon said stiff end, said closure comprising a rubber member having a cylindrical outer portion having a boss thereon and having a guide thereon for in-

dicating a cutting line, said closure being imperforate.

6. A closure for a collapsible tube, said closure including a body portion having a skirt thereon, said skirt having means thereon for engaging a collapsible tube, said body portion having an end portion thereon, and a resilient spring member arranged in said end portion, said spring member tending to maintain said end portion in normal position.

7. In combination with a collapsible tube, a closure secured upon said tube, said closure comprising a rubber member having an end portion and having a guide line thereon for indicating a cutting line, said closure being imperforate, said closure having a resilient strip therein, said strip extending substantially parallel to a side of said indicating line.

8. In combination with a collapsible tube having a flexible body and a stiff end, a closure removably secured upon said stiff end, said closure comprising a rubber member having a cylindrical outer portion having a boss thereon and having a guide line thereon for indicating a proper cutting line, said closure being imperforate, said closure having a resilient strip therein, said strip extending substantially parallel to the side of said indicating line.

9. A closure for a collapsible tube, said closure including a body portion having a skirt thereon, said skirt having means thereon for engaging a collapsible tube, said body portion having an end portion thereon, said closure having bosses disposed adjacent said end portion to increase the rigidity of the end portion and a resilient spring member arranged in said end portion, said spring member serving to increase the rigidity of the end portion.

In testimony whereof, I hereunto affix my signature.

ARTHUR E. SMITH.
